BOWL OR SIMILAR ARTICLE

Frank J. Benes, Lancaster, Ohio, assignor to Anchor Hocking Glass Corporation, Lancaster, Ohio, a corporation of Delaware

Filed Jan. 5, 1966, Ser. No. 487

Term of patent 14 years

(Cl. D44—15)

FIG. 1 is an elevational view of a bowl or similar article showing my new design;

FIG. 2 is a top plan view thereof;

FIG. 3 is a sectional view taken along line 3—3 of FIG. 2; and

FIG. 4 is a perspective view in smaller scale.

I claim:

The ornamental design for a bowl or similar article, substantially as shown.
